UNITED STATES PATENT OFFICE

2,565,603

DOLL

Edward Fraysur, Winchester, Ky.

Application February 19, 1946, Serial No. 648,622

4 Claims. (Cl. 46—118)

1

This invention relates to dolls, and more particularly to a mechanical doll having provisions, arrangements and mechanism for simulation in the doll of the going-to-sleep, awakening and accompanying sounds and movement of the limbs and with substantially the same effects and occurrences as with a natural live infant.

The special objects and advantages to be attained will be hereinafter more fully explained in connection with the accompanying drawings illustrative of a practical but non-limiting embodiment of the invention, in which:

Figure 1 is a view partly in longitudinal section and partly in elevation of a doll structure having provisions, arrangements and mechanism therein in exemplification of the invention;

Figure 2 is a view principally in elevation, but with parts broken away and shown in section, and mainly illustrating the location of the contained mechanism;

Figure 3 is a fragmentary detail view, on an enlarged scale, illustrating a form of spring motor for operating certain parts of the mechanism;

Figure 4 is a fragmentary detail view, on an enlarged scale, illustrative of a part of the ratchet operating means;

Figure 5 is a similar view of another part of the ratchet operating means;

Figure 6 is a detail view of a part of the winding means for the spring motor element; and

Figure 7 is a detail view of a part of the means for moving the arms and legs of the doll.

Referring now to the drawings in detail, the numeral 10 designates the main body portion of the doll which is hollow and made of any suitable rigid material or at least semi-rigid and form-retentive in character, the head portion 11 being also hollow. The neck portion 12 is also hollow so as to afford a communicating opening of ample size between the body portion and head portion.

The leg members 13 and arm members 14 of the doll, for the purposes of the present invention, are constructed so as to have at least limited movement therein. For this effect, said limb portions may be constructed of any suitable material and in any approved form and arrangement. As shown, leg members 13 and arm members 14 are attached integrally to the body portion 10 and these members are hollow throughout substantially the entire extent thereof. In the form illustrated, the upper portions of the legs and arms are more or less stiffened although the same are constructed of a relatively resilient material and they are generally form-retentive.

2

in character. However, at the crotch portions where the inner and outer portions of the legs and arms may be bent, said crotch portions are reduced somewhat in thickness to permit readily bending the members. In this connection, however, as far as the present invention is concerned, the legs and arms may be made in articulated or hingedly connected sections.

Associated with the openings in the head 11 for the eyes 15 are curved and dished lid members 16 which are hingedly mounted, as at 17, within the head (see Fig. 1). The lid mounting 17 comprises a common transverse rod or shaft which is pivotally supported at its opposite ends 18 in the adjacent side wall portions of the head, as at 19 (see Fig. 2).

As shown, a middle lever arm 19 extends from the pivotal shaft or rod 17 and the same is pivotally attached, as at 20, to a link member 21 (see Fig. 1). Said link member 21 may be made of a piece of stiff wire and provided at its free end and at a point intermediate its ends with stop portions 22 and 23, respectively, said stop portions, as shown, being produced by looping the link member 21 into eye formations. However, said stop portions may be produced in any other suitable manner.

An elongated lever bar or rod 24 is hingedly mounted, as at 25, on a supporting plate or base member 26, which latter is securely supported within the main body portion 10. As shown, the base member or supporting plate 26 is of substantially rectangular form and it is detachably secured at its two longitudinal corner portions 30 by screw elements or studs 27 which are embedded in the adjacent wall portions of the body 10. This base member or supporting plate 26 may be supported laterally by transverse rods or bars 28 attached to the lower longitudinal corner portions of the member 26 and being supported at their opposite ends in the adjacent side wall portions of the body 10. As to the form and arrangement of this supporting member 26, it is obvious that the same may be in other desirable or suitable form and attached in some other practical manner to the body 10.

One end portion of the lever bar or rod 24 which extends through the neck portion 12 of the doll body is provided with a loop or eye 29 or otherwise suitably apertured to slidably fit upon the link member 21 between the stop members 22 and 23. By this provision and arrangement of the lever member 24, and with said member 24 in the position shown in Figure 1, in which position the eye portion 29 is in contact with the end-

most stop portion 22 of the link 21, said link member 21 has been moved to a position whereby the eyelid member 16 is positioned to cover the eye 15. However, when the lever member 24 is tilted on its pivot 25, and its end portion which cooperatively engages the link member 21 is raised, the lid member 16 is moved to uncover the eye 15. At times during the pivotal movement of the lever member 24 between the full opening and closing positioning of the lid member 16, there is considerable lost motion between the stop portions 22 and 23 on the link member, whereby the lid member 16 remains in either its opened or closed position during these parts of the rocking movement of the lever member 24.

The pivotal mounting of the lever member 24, at the designated place 25, may be accomplished in any desired manner. For a certain purpose in the present invention, it is preferably mounted as indicated more clearly in Figure 2, wherein the pivot 25 comprises a headed stud on which the member 24 is swiveled, and between the member 24 and the base portion of the stud 25 there is provided a spring element 30 surrounding the stud and pressing the member 24 normally against the head at the outer end of the stud. By this provision, not only is an up-and-down rocking movement permitted of the lever, but the latter is also capable of a limited torsional and lateral movement on the stud 25, as will be later described more fully in detail. The other end portion of the lever member 24 is controlled and operated in a manner to be now described.

Mounted freely rotatable on a stud member 31 extending laterally from the base member or supporting plate 26 is a wheel 32 having peripheral ratchet teeth, said wheel 32 carrying a pinion 33 which meshes with a larger gear wheel 34 mounted freely rotatable on a stud 35 projecting laterally from the base member or supporting plate 26. In operation, the wheel 32, through its attached pinion 33, drives the wheel 34 and the latter, through a special supporting and lifting pin provision, controls the operation of the lever member 24. As shown, the gear wheel 34 is provided on one of its side faces with a pin 36 on which the adjacent end portion of the lever member 24 at times rests. The lever member 24 is held normally in contact with said pin 36 by a spring element 37 connecting the opposite end portion of said lever member 24 with an adjacent wall portion of the doll body and more specifically stated, as shown, the spring connection between the lever member 24 and the doll body is in the region of the neck portion of the body (see Fig. 1). Thus, with the adjacent end portion of the member 24 held in contact upon the pin 36 by the spring element 37, when the wheel 34 in the particular position and arrangement shown moves clockwise and thereby causes the pin 36 to travel in a circular path, this end portion of the lever member follows downwardly upon the pin 36 until the opposite end portion of the lever member 24 causes an opening movement of the eyelids 16. At a certain time during this clockwise rotation of the gear wheel 34, the eyelids 16 have moved to a fully opened position, whereupon the rocking movement of the lever member 24 ceases for the time being and the continued clockwise rotation of the gear wheel 34 carries the pin 26 away from the adjacent end portion of the lever arm 24 until the pin 36 has reached a diametrically opposite position. Thereafter, the pin 36, during the continued rotation of the wheel 34, again engages and rides under

the adjacent end portion of the lever member 24, thereby raising said adjacent end portion and lowering the opposite end portion of the lever member and effecting a closing movement of the eyelids 16, the fully closed position of the eyelids 16 being indicated as first hereinabove stated in Figure 1 of the drawings, and at which time the lever member 24 is in the position shown in full lines.

10 Special controlling and operating means for the driving wheel 32 and its pinion 33 is provided in accordance with the present invention, and this feature is an important feature. Any suitable provision and arrangement for imparting a 15 step-by-step or intermittent movement of the driving wheel 32 may be provided, but, in any case, it is preferable that such provision and arrangement be made whereby the actuation of the driving wheel 32 may be effected by moving the doll body either lengthwise or transversely, as will presently more fully appear.

20 As shown, a part of the means for actuating the driving wheel 32 comprises a ratchet element, designated generally by the numeral 38, and operated by a longitudinally swingable pendulum element 39. A somewhat similar ratchet element 40, operated by a transversely swingable pendulum element 41, is also provided in addition to said parts 38 and 39.

25 30 The elements 38 and 39 are shown more clearly in Figure 4, while the elements 40 and 41 appear more clearly in Figure 5. As shown, the ratchet element 38 is pivotally mounted, as at 42, on the base member or supporting plate 26, and the ratchet member 40 is similarly mounted on said member 26, as at 43. The elements 38 and 40 are each yieldably held against a stop lug or pin 49 by a spring 50.

35 40 The member 38, as shown in Figure 4, comprises a substantially rectangular body plate 54 carrying at one end portion a pivotally mounted pawl 55 which normally engages the peripheral ratchet teeth on the drive wheel 32. The pawl 55 is held normally against a stop projection or shoulder 56 provided on the adjacent end portion of the plate member 54 by a spring element 57, the particular provision and arrangement being such that the pawls 55, in engagement with the peripheral teeth of the wheel 32, causes a partial rotation of the wheel when either the ratchet element 38 or 40 is rocked in one direction on its pivot 42 or 43, while the spring elements 57 permit either pawl 55 to move with escapement effect on the peripheral teeth of the wheel 32 when the ratchet element is rocked in the opposite direction. This provision and arrangement permits the wheel 32 to be moved in one direction, but prevents movement in the opposite direction. So, too, in this connection, to prevent reverse rotation of the drive wheel 32 when the ratchet element 38 is moved in the direction to again engage the wheel for the feeding of the same, the spring-pressed dog 48 is provided on the base member or supporting plate 26 to normally engage the peripheral teeth on the driving wheel 32. The ratchet element 38 is held in normal position against a stop stud 49 by a spring element 50 which urges said element toward and against said stud 49. The opposite end portion of the ratchet element 38 is provided with a lateral cam projection 51 which is beveled at its end and engaged by a correspondingly beveled cam portion 52 on the adjacent end portion of the pendulum element 39. The pendulum element 39 is provided with a 45 50 55 60 65 70 75 weighted head 53 which normally holds the ele-

ment 39 in a pendent position and causes a swinging movement of said element 39 when the doll is moved or rocked endwise.

As hereinabove stated, the ratchet element 40 is somewhat similar to the element 38, that is to say, in its general character, and the provisions for its operation. As shown in Figure 5, the element 40 comprises a body plate 54 which is hingedly mounted on the base member or supporting plate 26, as at 43. This body plate 54 carries a pawl 55 similar to the aforesaid other pawl 55. This pawl 55 engages the peripheral ratchet teeth of the drive wheel 32 in substantially the same manner as the aforesaid pawl 55 and the same is held normally against the stop projection or stud 56 by a spring element 57 provided on said body plate 54. The body plate 54 is provided with a tail extension 58 which is engageable and operated by a cam portion 59 provided on the pendulum 41. Said pendulum 41 is also provided with a weighted head 60 similar to the head 53 on the pendulum 39. The pendulum 41 acts upon the tail extension 58 of the ratchet element 40 in substantially the same manner as the element 39 acts upon the cam projection 51 of the ratchet element 38, except that the pendulum 41 swings transversely of the doll body instead of lengthwise thereof.

With the constructional provisions and arrangements thus far described, it is here noted that if the doll body is swayed or rocked either longitudinally or transversely when held in the arms or placed in a cradle or rocking chair or the like, the doll's eyes will be caused to close and open at intervals in simulation of substantially the same effect as in the handling of a natural and live infant. Other essential features of the invention will now be described.

In the illustrated construction and arrangement as thus far described, it is here pointed out, in particular, that while the driven gear wheel 34 rotates in a clockwise direction, the driving wheel 32 and its attached pinion 33 are obviously caused to rotate in a counter-clockwise direction by operation of the respective ratchet elements 38 and 40. The stressed mention of this particular direction of rotation of the driven gear wheel 34 is because the same has a material operating effect upon certain additional essential features of the device.

As shown, a conventional sound-producing element 61 is provided within the body portion 19 of the doll. This device, which may be of any approved form and character, is to produce, controllably, different characters of sounds varying from a mild sound or whimper to a loud and vociferous cry in simulation of such in real life as an infant awakes either gradually or suddenly. As indicated more or less conventionally and schematically in the drawings, the sound-producing device is of the bellows type. As shown, it is suitably positioned and mounted on an adjacent wall portion of the body 18 of the doll, within the hollow thereof and adjacent the aforesaid and hereinafter described operating and controlling mechanism, said sound-producing element 61 having a rod element 62 attached at one end thereto, while the other end of the rod 62 is provided with a substantially hinged and compensating attachment to an end extension 63 of the aforesaid lever member 24, as at 64.

The conventional provisions and arrangements within the bellows 61 (obvious and not shown) are such that upon the movement of the rod 62 in one direction to compress the bellows, by a relatively slow movement, only a slight murmur-

ing or whimpering sound is produced by the element. This effect is attained as the gear wheel 34 rotates in a clockwise direction and permits the comparatively slow lowering of the adjacent end portion of the lever member 24 under the influence of the spring element 37 which holds said member 24 in contact with the pin 36 on the gear wheel 34. However, if the supported end portion of the lever member 24 is suddenly removed from the supporting pin 36, so that the spring element 37 causes a sudden and rapid movement of the lever member, the rod 62 is accordingly forcibly and rapidly actuated, whereupon the element 61 gives forth a loud and vociferous sound in simulation of an infant when startled or suddenly awakened. A suitable provision for effecting the sudden and rapid actuation of the lever member 24 will now be described.

A suitable tripper element 65 is provided, the same being attached, as at 66, to the base member or supporting plate 26. The element 65, as shown, comprises a resilient strip which is extended from its supported end portion 66 diagonally across and closely adjacent to the extension 63 on the lever member 24, the free end portion of said element 65 being extended to overlap the face portion of a gear wheel 67. The gear wheel 67 is mounted to rotate on a stud 68 adjacent to the periphery of the driven gear 34. Said gear wheel 67 is provided on its face portion with one or more stud members 69 and it is driven by a spring motor of a conventional type and including a clock or watch mechanism to give a timed actuation to the wheel 67. The free end of the tripper 65 is diagonally directed, as at 65, to provide a cam surface which is disposed in the path of the studs 69. Thus, as a stud 69 engages the cam surface 65, the tripper is moved laterally into engagement with the extension 63 of lever 24 whereby to move the latter laterally beyond the end of the pin 36 of gear 24 for a purpose to be apparent hereinafter.

The timed spring motor is designated generally by the reference numeral 70. As just above noted, it is of a more or less conventional type, but it has in connection therewith certain features of detail to be now described.

As shown more clearly in Figure 3, the motor 70 comprises an annular housing in which there is located a spring element 71, the attachment of said spring element to the annular housing being of the type whereby the end of the spring is substantially retained in working position, yet slippage is permitted under forced winding of the spring to prevent overwinding of the same. That is to say, the outer end portion of the spring element 71 is formed sinuously or corrugated transversely, as at 72, and this peculiarly formed end portion of the spring engages over a hump or protrusion 73 on the inner peripheral face of the housing (see Fig. 3). The inner end portion of said spring element 71 is attached, as at 74, to the axial rotor or staff 75 of the motor.

Through the medium of a suitable chain of gearing (not shown), the rotor or staff 75 of the motor is driven by a ratchet provision on the outside of the motor housing 70. This ratchet driving provision is shown more clearly in Figures 1 and 6 of the drawings, wherein it comprises a ratchet wheel 76 which is cooperatively connected to the internal gearing (not shown) for driving the rotor or staff 75 in one direction to wind the spring element 71. In this connection, it is here noted that the said internal gearing

of the motor (not shown) includes also a ratio gear (not shown) which is in mesh with the peripheral teeth of the aforesaid gear 67 whereby the latter is rotated constantly so that the facial stud or studs 69 on said gear 67 intermittently engage the cam surface 165 on the free end portion of said tripper element 65 which in turn pushes the adjacent end portion of said lever member 24 off the supporting pin 36 on said driven gear 34, thereby permitting the lever 24 to drop suddenly and actuate the sounding device 61 so as to cause a loud cry.

For operating the ratchet wheel 76 to wind the spring of the motor, an operating lever is pivotally mounted so as to be rockable freely on the shaft of said ratchet wheel 76, said operating lever 77 being yieldably held in normal position against a stud member 78 by a spring element 79. A shorter end portion of said operating lever 77 carries a spring-pressed pawl 80 which normally engages the peripheral ratchet teeth on the wheel 76. A longer end portion of said operating lever 77 is extended to overlap the side face of said driven gear 34 opposite to that on which the aforesaid pin 36 is provided, said driven gear 34, on said face which is overlapped by the operating lever 77, being provided with at least one pin 81, but, preferably, a plurality of such pins in annularly spaced relation to each other. By this particular provision and arrangement, as the gear wheel 34 rotates in its clockwise direction, said pin or pins 81 intermittently strike said operating lever 77 and cause an actuation of the same to in turn cause a partial rotation of said ratchet wheel 76. This actuation of the ratchet wheel 76 causes a winding action on the spring element 71 of the motor at frequent intervals, and, as hereinabove stated, the particular provision of the outer end portion of the spring for sequential engagement of the same with the spring barrel or housing of the motor prevents overwinding of the spring. In this connection, it is here also noted that the prevention of overwinding may be attained in various manners other than that specifically shown. As shown in Figure 3, there is provided only one hump or protuberance 73 on the spring barrel and there are only a limited number of the undulations or transverse corrugations 72 provided in the end portion of the spring. Obviously, however, in some cases, only one undulation or corrugation 72 may be provided in the spring end portion and a series of the humps or protuberances 73 may be provided on the spring barrel. So, too, in other cases the interengaging provision between the spring barrel and the end portion of the spring may be made continuous throughout the circular extent of the spring barrel.

As the invention is thus far described, it is clearly apparent that the doll can be placed in the simulation of sleep by swinging or rocking the body either endwise or transversely or alternately in either direction. Moreover, such rocking serves to wind the motor 70 as previously described which drives the gear 67 continuously. Thus, after the eyes have been made to appear as closed in sleep, the doll may be left alone so that, upon the timed operation of the controlling mechanism or mechanisms so far described, an automatic opening of the eyes is accomplished, and in which latter instance, by the provision for effecting the sudden and rapid movement of the operating lever 24, the sounding device 61 is made to give forth a loud and vociferous crying

sound rather than a slow and murmuring or whimpering sound. The latter effect is attained by deliberately manipulating the body of the doll to continue rotation of the gear 34 and a consequent lowering of the adjacent end portion of the lever member 24, which effect is attained with different degrees of rapidity depending on the speed in which the body of the doll is swayed or rocked either endwise or transversely.

In addition to the aforesaid explained features of the present invention, provision is made for moving the arms and legs of the doll upon the attainment of the awakening effect. For this purpose, as herein first described, the limbs of the doll are made so as to be movable at least to a certain degree. As shown, cords, wires or other flexible elements 82 are extended into the hollow leg members of the doll and attached to the foot portions, as at 83. These flexible elements 82 are carried through guides 84 located adjacent the knee joints of the legs, thence through apertures 85 in the body portion 10 in the region where the legs are attached thereto, and then through suitable guide elements 86, whence the two leg flexible elements 82 are joined to a rockable element 87 which is pivotally mounted, as on a shaft 88, on the base member or supporting plate 26. Similarly, flexible members 89 are attached at their outer ends, as at 90, to the hand portions of the arms 14, thence through guides 91, apertures 92, where the arms join the doll body 10, then through guides 93, from which guides the inner ends of the flexible members 89 are attached to said rockable member 87. Obviously, as said rockable member 87 is swung in either direction, the flexible elements 82 and the corresponding elements 89 are alternately drawn tightly in one direction and loosened in the opposite direction, which alternate action causes a corresponding alternate movement of the legs and arms of the doll. In this connection, it is noted that if the oscillation of the rockable member 87 is comparatively slow, the movement of the doll limbs is correspondingly slow, whereas, if the oscillation of the rockable member 87 is rapid, the limbs accordingly move with corresponding rapidity.

To effect oscillation of the rockable member 87, the same is connected by link element or pitman 94 to a crank wheel 95, which latter is pivotally mounted, as at 96, on the base member or supporting plate 26. This crank wheel 95 is provided on its periphery with ratchet teeth which are engaged by a ratchet toothed rack bar 196, which latter is pivotally mounted, as at 97, at one end on the lever member 24. The lower end portion of said rack bar 196 is provided with the ratchet teeth, which end portion is normally held in engagement with the periphery of the crank wheel 95 by a spring element 98, said spring element holding the rack bar normally in engagement with the wheel 95 so as to effect at least a partial rotation of the wheel 95 upon a downward movement of the adjacent end portion of said lever member 24. However, it is preferable to have the ratchet teeth on the rack bar extended for a considerable distance longitudinally of the bar so as to give a full rotation of the wheel 95 or possibly a multiple rotation thereof during the downward movement of the rack bar. As the crank wheel 95 is thus rotated, the link or pitman connection 94 between the wheel and the rocker element 87 effects an oscillatory movement of said element 87. Of course, if the downward movement of the rack bar 96 is compara-

tively slow, the oscillation of the rocker element 87 is correspondingly slow, but if the downward movement of the rack bar 96 is sudden and rapid, the crank wheel 95 is accordingly rotated rapidly and imparts a rapid motion to the rocker element 87. This rapid operation of the crank wheel 95 occurs when the awakening effect of the doll occurs suddenly under the mechanical controlling and operating means, thus causing a simulated outcry of the doll and at the same time causing the legs and arms to kick or move rapidly.

It is here noted that the rockable element, indicated generally by the numeral 87, may be of any suitable and approved construction and arrangement. As indicated more clearly in Figure 7 of the drawings, it comprises a transverse rock-shaft 88 supported rotatably in a boss 100 provided on the base member or supporting plate 26 (see Fig. 2) and having a relatively short lever-arm 101 to which the pitman link 94 is pivotally attached (see Fig. 7). This rock-shaft 88 has an upturned arm 102 at one end, to which arm the ends of one each of the leg and arm operating cords 82 and 89 are attached. The other end of the shaft 88 has a downturned arm 103 to which the two others of the cords 82 and 89 are attached (see Figs. 2 and 7). This is one practical provision and arrangement. As above stated, the same may be varied in different adaptations of the invention.

It is here further noted that the rack-bar 196 may be movably held and guided by a clip element 104 of any suitable kind and mounted on the base member or supporting plate 26.

From the foregoing it is apparent that a doll is produced which can be handled and made to simulate the true characteristics of a living infant, thereby making dolls more interesting and teaching and indicating to a child the care and attention in simulation to that of a living infant.

Obviously, while the illustration exemplifies a practiced embodiment of the invention, it is understood that considerable modification is contemplated as to the general structure as well as the details thereof. The invention, therefore, is not limited to the specific construction and arrangement shown.

What is claimed is:

1. A simulative sleeping doll comprising a body having a head provided with openable and closable eyelids, mechanism within the body for moving the eyelids to opened and closed position by a back-and-forth movement imparted to the body either longitudinally or laterally thereof, said mechanism including two weighted pendulum elements swinging in planes at right angles to each other and each operating a separate ratchet mechanism to effect rotation of a single controlling wheel, said wheel carrying a supporting member traveling thereon in a circular path, a lever member having an operative connection with the eyelids for effecting a closing movement of the eyelids in one direction and an opening movement of the same when operated in the opposite direction, said lever member resting normally on said supporting member of the controlling wheel whereby to be lowered during a part of the rotation of said wheel and lifted during the rest of its rotation, timed mechanism for displacing said lever member from said supporting member on the controlling wheel during the time of closed position of the eyelids, a spring motor for operating said timed mechanism, the spring of the motor being intermittently wound by a co-

operative provision between the same and the controlling wheel.

2. The doll construction and arrangement as set forth in claim 1, wherein the doll body is provided with a sound-producing element therein and cooperatively connected to said lever member whereby to produce a relatively slow murmuring sound during the opening movement of the eyelids when the lever element is supported on said supporting member of the controlling wheel but produces a louder sound upon the sudden displacement of said lever member from said supporting member on the controlling wheel.

3. A simulative sleeping doll construction and arrangement as set forth in claim 1, wherein the doll body is provided with a sound-producing element therein, the same being operatively connected with the lever arm whereby to produce a relatively slow murmuring sound during the opening movement of the eyelids while the lever arm is supported on said supporting member of the controlling wheel, but produces a louder sound upon the sudden displacement of said lever member from said supporting member on the controlling wheel, and connected means within the body and limb portions of the doll for moving the limbs with slow agitation during the opening of the eyelids under the control of said controlling wheel but moving the limbs with quicker agitation when said lever member is suddenly displaced from the supporting member on said controlling wheel.

4. A simulative sleeping doll comprising a body having a head provided with openable and closable eyelids, a controlling wheel disposed within said body and rotatably supported therein, means connected to said controlling wheel and actuatable in response to a back and forth movement imparted to said body either longitudinally or laterally thereof for effecting the rotation of said controlling wheel, a lever rockably supported intermediate its ends within said body and having one end operatively connected to said eyelids for effecting a closing movement of the latter upon rocking movement of said lever in one direction and an opening movement of the same upon rocking movement of said lever in the opposite direction, a supporting member carried by a face of said control wheel and engageable with said lever for effecting the rocking movement of the latter in timed sequence during a rotational cycle of said control wheel, timed mechanism operatively connected to said lever for displacing the latter from engagement with said supporting member during the time of the closed position of said eyelids, a spring motor operatively connected to said timed mechanism for operating the latter, and means operatively connecting said spring motor to said controlling wheel for intermittently winding the former in response to the rotational movement of the latter.
